Primary Examiner—A. Hugo Word

[57] **CLAIM**

The ornamental design for a small revolver with hammer, substantially as shown and described.

DESCRIPTION

FIG. 1 is a left side perspective view of the revolver of the present invention;

FIG. 2 is a left side elevational view thereof;

FIG. 3 is a right side elevational view thereof;

FIG. 4 is a top plan view thereof;

FIG. 5 is a bottom view thereof;

FIG. 6 is a front elevational view thereof;
FIG. 7 is a rear view thereof;
FIG. 8 is a right side perspective view thereof;
FIG. 9 is a right side elevational view of the modification thereof;
FIG. 10 is a partial right side perspective view of the modification thereof;
FIG. 11 is a left side elevational view of the modification thereof;
FIG. 12 is a partial left side perspective view of the modification thereof;
FIG. 13 is a top plan view of the modification thereof;
FIG. 14 is a front elevational view of the modification thereof;
FIG. 15 is a rear elevational view of the modification thereof;
FIG. 16 is a right side perspective view of the modification thereof;
FIG. 17 is a right side perspective view of the modification thereof;
FIG. 18 is a left-hand elevational view of a further modification thereof;
FIG. 19 is a right-hand elevational view of the modification thereof;
FIG. 20 is a top plan view of the modification thereof;
FIG. 21 is a bottom plan view of the modification thereof;
FIG. 22 is a front elevational view of the modification thereof;
FIG. 23 is a rear elevational view of the modification thereof;
FIG. 24 is a left-hand perspective view of the modification thereof; and
FIG. 25 is a right-hand perspective view of the modification thereof.
